UNITED STATES PATENT OFFICE.

ANDREW B. CHRISTENSEN, OF CHICAGO, ILLINOIS, ASSIGNOR TO THE THISTLE MANUFACTURING COMPANY, OF CHICAGO, ILLINOIS, A CORPORATION OF ILLINOIS.

GEARING FOR WASHING-MACHINES.

No. 845,615.

Specification of Letters Patent.

Patented Feb. 26, 1907.

Application filed December 14, 1906. Serial No. 347,744.

To all whom it may concern:

Be it known that I, ANDREW B. CHRISTENSEN, a citizen of the United States, a resident of Chicago, in the county of Cook and State of Illinois, have invented certain new and useful Improvements in Gearing for Washing-Machines, of which the following is a full, clear, and exact description.

My invention relates to certain new and useful improvements in gearing for washing-machines of that class in which a beater within the tub or other clothes-receptacle has imparted to it a rotary reciprocatory movement, and more particularly to machines of this class which contain mechanism for storing up in a fly-wheel part of the energy or force exerted to drive the beater, whereby continued application of power on the part of the operator becomes unnecessary, the stored-up power serving to drive the beater after the exertions of the operator ceases until the stored-up energy is exhausted.

One of the objects of my invention is to simplify and cheapen the construction of gearings of this type.

Another object is to provide means whereby a greater amount of power may be stored up with the same amount of energy on the part of the operator.

Another object is to provide means whereby the energy applied to the operating-lever may be communicated directly to the fly-wheel and independent of the other mechanism which operates the beater. To such end my invention consists of certain novel features of construction and arrangement, a description of which will be found in the following specification and the essential feature more particularly pointed out in the claims appended hereto.

The invention is clearly illustrated in the drawings accompanying this specification, in which—

Figure 1 is a plan view. Fig. 2 is a side view thereof looking in the direction of the arrow 2 in Fig. 1. Fig. 3 is a similar view with the fly-wheel removed, the fly-wheel shaft and pinion being shown in vertical cross-section and the operating parts in a different position from that in which they are shown in Fig. 2. Fig. 4 is a view, partly in side elevation and partly in vertical cross-section, of the beater and its connections with

the operating-lever, the line of section being indicated at 4 4 in Fig. 1. Fig. 5 is a plan view of a frame or bracket in which the operating parts are mounted. Fig. 6 is a side view thereof looking in the direction of the arrow 6 in Fig. 5, and Fig. 7 is a front view thereof looking in the direction of arrow 7 in Fig. 5 and showing certain of the operating mechanism.

Referring to the drawings, 10 represents a tub or clothes-receptacle of ordinary construction which is provided with a cover or lid 11, hinged to a stationary part 12 of the tub. The cover may be locked down in its closed position by any suitable hasp or lock 13, as shown in the drawings. Upon the cover 11 is mounted a bracket or frame 20, (see Figs. 5, 6, and 7,) which is preferably secured to the cover by means of bolts or screws 21. Said bracket contains two members or arms 20^a 20^b, and a pair of standards 22 extend up from the member 20^b, in which is journaled the rock-shaft 30, whose movement is effected by an operating-lever 40. The bracket 20 contains a downwardly-projecting journal-bearing 23, in which is journaled a beater-shaft 50, which carries a beater 51.

The beater-shaft and beater are of the ordinary construction common to machines of this kind and require no detailed explanation, the only requisite being that the beater shall be vertically movable upon the beater-shaft and connect thereto against relative rotation. A bevel-pinion 52 is mounted upon the upper end of the shaft 50 and meshes with a segmental rack 31, fast upon the rock-shaft 30. It is evident that oscillatory movement of the segment will cause corresponding oscillatory movement of the beater-shaft and beater.

The operating-lever 40 is secured upon one end of the rock-shaft 30 and consists, preferably, of a bell-crank rocker member 41, one arm of which, 42, is perforated to receive the handle 43 of the lever, and the other arm 44 of which is connected, by means of a pitman 60, with a gear-wheel 61. The gear-wheel 61 is journaled upon a stud 24, projecting out from the member 20^a of the bracket or frame 20. The gear-wheel 61 meshes with a pinion 71, which is preferably formed integral with a fly-wheel 70, and said fly-wheel is journaled

upon a stud 25, which also extends out from the member 20^a of the frame 20. The gear-wheel 61 and fly-wheel are preferably held in place upon the studs by means of cotter-pins 5 60^a and 70^a.

The operation of the machine is as follows: The tub is first filled with water and the clothes to be washed and the cover fastened down. The lever 40 is then oscillated to 10 rock the shaft 30, the rocking movement of which is transmitted, by means of the gearing, to the beater, causing a corresponding rocking or rotary reciprocatory movement thereof. The rocking or oscillatory movement of the operating-lever is transformed 15 into a continuous rotary movement of the gear-wheel 61, which by reason of its connection with the fly-wheel causes the same to revolve at a very high speed as compared with 20 the movement of the rock-shaft 30. Considerable of the energy or force which is exerted to operate the beater is taken up and stored in the fly-wheel, so that the same will 25 continue to operate the lever, and consequently the beater, after the exertions of the operator have ceased and until said stored-up power is exhausted. The advantages of this construction are obvious: In the first place, the energy is transferred directly from the 30 operating-lever to the power-storing mechanism independent of the rock-shaft 30, and because of this direct connection less power is required to store up energy and more power in turn will be given to the rocker-arm from 35 the fly-wheel than where the connections between the operating-lever and fly-wheel are transmitted through the shaft 30 and other complicated mechanisms. In a device of this kind friction plays an important part, and 40 when this friction can be reduced to a minimum the power or force required to store up a certain amount of energy will obviously be a great deal less than where a great amount of friction is encountered in the mechanism for 45 transferring the energy.

I am aware that various alterations and modifications of the device are possible, and I do not, therefore, desire to limit myself to the exact construction shown and described.

50 I claim as new and desire to secure by Letters Patent—

1. In a device of the class described, the combination with a beater-shaft and a rock-shaft connected thereto, of an operating-lever 55 arranged to rock said rock-shaft, a fly-wheel and connections between the operating-lever and fly-wheel independent of said rock-shaft, adapted to transform the oscillatory movement of the operating member to a continuous rotary movement of the fly-wheel.

60 2. In a device of the class described, the combination with a beater-shaft and rock-shaft geared thereto, of an operating-lever arranged to rock said rock-shaft, a fly-wheel,

and connections between the operating-lever 65 and fly-wheel independent of said rock-shaft for transmitting the oscillatory movement of the operating-lever to a continuous rotary movement of the fly-wheel.

3. In a device of the class described, the 70 combination with a beater-shaft and rock-shaft geared thereto, of an operating-lever secured to the rock-shaft and adapted to rock the same, an arm upon said operating-lever, a fly-wheel, and connections between 75 said arm and fly-wheel independent of said rock-shaft adapted to transform the oscillatory movement of the arm to a continuous rotary movement of the fly-wheel.

4. In a device of the class described, the 80 combination with a beater-shaft and rock-shaft geared thereto, of a bell-crank rocker member arranged to impart a rocking movement to the rock-shaft, a fly-wheel, gearing for rotating said fly-wheel at a high rate of 85 speed as compared with the speed of the rock-shaft, and a pitman connecting said rocker member with said gearing independent of 90 said rock-shaft and arranged to transform the oscillatory movement of the rocker member to a continuous rotary movement of the fly-wheel.

5. In a device of the class described, the combination with a beater-shaft and a rock-shaft geared thereto, of a fly-wheel a rocker 95 member arranged to rock said rock-shaft and means of connection independent of said rock-shaft between said rocker member and the fly-wheel arranged to transform the oscillatory movement of the rocker member to a 100 continuous rotary movement of the fly-wheel.

6. In a device of the class described, the combination with a beater-shaft and a rock-shaft geared thereto, of a rocker member for 105 said rock-shaft, a fly-wheel, a gear-wheel geared thereto and a pitman connecting said gear-wheel with the rocker member and adapted to transform the oscillatory movement of the rocker member to a continuous rotary movement of the fly-wheel.

7. In a device of the class described, the combination with a bracket having laterally-projecting studs, of a beater-shaft and rocker-shaft journaled therein, connections between 115 said shafts, a rocker member arranged to impart a rocking movement to said rock-shaft, a fly-wheel journaled upon one of said studs and carrying a pinion, a gear-wheel journaled upon the other stud and a pitman connecting the rocker with said gear-wheel.

120 In witness whereof I have executed the above application for Letters Patent, at Chicago, county of Cook, and State of Illinois, this 10th day of December, 1906.

ANDREW B. CHRISTENSEN.
